METHOD OF ANALYZING MIXED ORGANIC
ACID ESTERS OF CELLULOSE

Carl J. Malm and Gale F. Nadeau, Rochester,
N. Y., assignors, by mesne assignments, to
Eastman Kodak Company, Jersey City, N. J., a
corporation of New Jersey

No Drawing. Original application March 6,
1933, Serial No. 659,698. Divided and this
application November 24, 1934, Serial No.
754,680.

8 Claims. (Cl. 23—230)

The present invention relates to the determination of the contents of acetic acid, and of fatty acids of 3-4 carbon atoms in an aqueous solution by determining the percentage partition coefficient of the solution in a water-insoluble liquid fatty acid ester of a lower aliphatic monohydroxy alcohol. It also involves the determination of the content of acetyl and fatty acid groups of 3-4 carbon atoms in a cellulose ester. This application is a division of our application Serial Number 10 659,698, filed March 6, 1933.

In view of the growing importance of the mixed organic acid esters of cellulose such as cellulose acetate propionate and cellulose acetate butyrate a method of analysis whereby the percentages of the various acyl groups may be accurately determined is highly desirable. Various methods have been proposed for analyzing mixtures of fatty acids; however there is usually at least one disadvantage met with in their practical use. For instance, some methods are suitable when each of the acids constitutes a substantial percentage of the mixture; however when one of those acids is only about 5% or less the results are not sufficiently accurate, especially where butyric acid is present in small amount.

One object of our invention is to provide a method for analyzing for acetyl, propionyl and butyryl particularly when two or all of these groups are combined with cellulose. Another object of our invention is to provide a method for analyzing a mixture containing acetic, propionic and butyric acids in which the butyric acid may be present in small amount without abridging the accuracy thereof. Other objects will appear herein.

The present invention involves the partition method for the analysis of acid mixtures by means of an extractant selected from the water-insoluble liquid fatty acid esters of the lower aliphatic monohydroxy alcohols, such as n-propyl acetate, n-butyl acetate, ethyl n-butyrate, etc. It also involves the hydrolysis of the acyl groups from the cellulose ester containing them preliminary to the analysis proper.

Our method of analysis of, for instance a mixed organic acid ester of cellulose, is carried out by first treating the ester with a hydrolyzing base such as aqueous alkali until the acyl groups therein have all been hydrolyzed off from the ester. The solution which comprises the alkali metal salts of the organic acids and any alkali over that necessary to neutralize these groups is then treated with dilute high boiling mineral acid such as phosphoric,

in an amount which will exactly combine with the alkali metal content of the solution.

The whole is then subjected to distillation to separate off the organic acids preferably so that the normality of the distillate approaches 0.1 although any concentration of distillate is satisfactory for carrying out the analysis with accuracy. By determining the amount of standard alkali necessary to neutralize a given amount of the distillate and by determining the percentage partition between water and the extractant the percentages of the various acyl groups may be calculated as described in the specific example.

Obviously this method of analysis may be adapted to various modifications by those skilled in the art, such as changing concentrations and still be within the scope of the present invention.

The following example illustrates the analysis of a cellulose ester containing acetyl, propionyl and butyryl groups by the present invention. Obviously if an ester containing only acetyl and propionyl or acetyl and butyryl groups is to be analyzed the calculations need not be as involved as when there are three different acyl groups present, however, often the cellulose acetate propionate produced commercially has a small butyryl content and commercial cellulose acetate butyrate may contain some propionyl so that the method described in the example will ordinarily be used.

A 2 gm. sample of the cellulose ester to be analyzed is placed in a 500 c. c. round bottom short neck flask and treated with 80 c. c. of 0.5 N alkali (aqueous sodium or potassium hydroxide). The flask and contents are maintained at 40° C. for 48 hrs. The solution is then acidified with 30 molar phosphoric acid, the volume of phosphoric acid necessary having been previously determined by titration of a sample of the .5 N alkali with the phosphoric acid. Methyl orange is employed as the indicator. (The use of methyl red is not advised for the most accurate work because its color changes at a higher pH value than methyl orange.)

The flask is then fitted with a two hole rubber stopper equipped with a Kjeldahl trap (for spray) and a capillary tube for the vacuum distillation of the organic acids. An ordinary straight inner tube condenser is connected to the Kjeldahl trap and a 500 c. c. Engler distillation flask is used for the receiver. The end of the condenser should extend down into the receiver flask which is packed with ice and salt (or cooled below 0° C. by any other appropriate means). The distillation flask is immersed in a

water bath whose temperature is about 90° C. Operating at this temperature with a pressure in the system of about 20 m. m. the flask becomes dry after about 2½ hours. The distillation must be continued after the flask is apparently dry in order to remove the saturated vapor and liquid which collects in the trap.

When the flask and bulb are dry, the trap and flask are rinsed with about 10 c. c. of water and 10 the distillation is again carried to dryness after which this operation is repeated. The condenser is finally rinsed into the receiver and the distillation will approximate five hours.

Twenty-five c. c. of the distillate are titrated 15 with standard alkali. The volume of alkali required is designated M. Thirty c. c. of the distillate are then extracted with 15 c. c. of n-propyl acetate, the aqueous layer being removed and 20 25 c. c. of it titrated with the standard alkali. The volume of alkali required for this titration is designated as M_1 . The extraction is again carried out using 30 c. c. of the distillate with 60 c. c. of n-propyl acetate. The volume of alkali necessary to titrate 25 c. c. of the aqueous phase in 25 this case is designated as M_2 . These values are substituted in the equations

$$30 \quad \frac{100M_1}{M} = K_1$$

$$\frac{100M_2}{M} = K_2$$

in which K_1 and K_2 are termed the percentage 35 partition coefficients. They represent the percentage of the original acid which remains in the aqueous phase after the extraction in each case. If the value is desired in a decimal fraction instead of in percentage the multiplication by 100 40 will of course be omitted. From these values the acetyl, propionyl and butyryl contents of the ester can be calculated as follows:

In the following equations let k_1 =percentage 45 partition coefficient of 30 c. c. of .1 N acetic acid with 15 c. c. of propyl acetate.

k_2 =percentage partition coefficient of 30 c. c. of .1 N propionic acid with 15 c. c. of propyl acetate.

k_3 =percentage partition coefficient of 30 c. c. of .1 N butyric acid with 15 c. c. of propyl acetate.

k_4 =percentage partition coefficient of 30 c. c. of .1 N acetic acid with 60 c. c. of propyl acetate.

k_5 =percentage partition coefficient of 30 c. c. of .1 N propionic acid with 60 c. c. of propyl acetate.

k_6 =percentage partition coefficient of 30 c. c. of .1 N butyric acid with 60 c. c. of propyl acetate.

These values are determined in the laboratory 60 by extraction of .1 normal solutions of pure acids in the same manner as described above for an unknown solution. These values upon determination in the laboratory were found to be as follows:

65 Acetic acid $k_1=.816$ $k_4=.534$
Propionic acid $k_2=.550$ $k_5=.236$
Butyric acid $k_3=.265$ $k_6=.086$

70 In order to evaluate three unknown quantities one must have three simultaneous algebraic equations involving them. In the case of a ternary acid mixture obviously the sum of the mol. percentages of the acids present will be 100%. If 75 A, P and B are allowed to represent respectively

the mol. percentages of acetic, propionic and butyric acids, we have the equation:

$$(1) A+P+B=100$$

As K_1 and K_2 are the sums of the percentage 5 partition coefficients in the respective extractions, we have the equations:

$$(2) AK_1+PK_2+BK_3=K_1$$

$$(3) AK_2+PK_1+BK_4=K_2$$

Solving for P the equation:

$$P = \frac{\frac{K_1-100K_1}{K_1-K_1} - \frac{K_2-100K_2}{K_2-K_2}}{\frac{K_2-K_1}{K_1-K_1} - \frac{K_3-K_4}{K_2-K_4}} \text{ is obtained}$$

15 By substituting the values of k subs 1, 2, 3, 4, 5 and 6 as determined, the equation simplifies to

$$P=9.95(K_1-81.6)-12.23(K_2-53.4)$$

In a similar manner, B is found to be expressed 20 by the equation,

$$B=2.232(53.4-K_2)-0.665P$$

As $A=100-P-B$ the mol. per cent of acetic acid may be readily calculated. Obviously this 25 method is also applicable to the analysis of cellulose acetate propionate and cellulose acetate butyrate.

In the case where the third acyl is substantially entirely absent there need be carried out 30 only one extraction for instance with 15 c. c. (or with 60 c. c. as desired) of the extractant and the value for only one "percentage partition coefficient" which is designated by K_1 or by K_2 is necessary. As there are only two unknowns 35 only two simultaneous algebraic equations are necessary and these may be for instance:

$$A+P=100$$

$$Ak_1+Pk_1=K_1$$

40 where propionyl and acetyl only are involved and it is desired to use 15 c. c. of the extractant in the extractions.

Solving these equations for P

$$P = \frac{100k_1-K_1}{k_1-k_1} \text{ is obtained}$$

45 If it is desired to use 60 c. c. of the extractant the equations will be:

$$A+P=100$$

$$Ak_4+Pk_4=K_2$$

from which

$$P = \frac{100k_4-K_2}{k_4-k_4} \text{ is obtained}$$

55 Where acetyl and butyryl only are involved and using 15 c. c. of extractant the equations may be:

$$A+B=100$$

$$Ak_1+Bk_3=K_1$$

from which

$$B = \frac{100k_1-K_1}{k_1-k_1} \text{ is obtained}$$

60 By substituting the values of k_1 and k_3 , as determined, in the formula

$$P = \frac{100k_1-K_1}{k_1-k_1}$$

70 the equation simplifies to:

$$P = \frac{81.6-K_1}{.266}$$

Obviously if the operator of an analysis in accordance with the present invention desires to use other quantities of the extractant than those specified, such a modification is permissible 5 without departing from the scope of the present invention.

To illustrate the present method of analysis the data from the analysis of a cellulose acetate propionate containing a small amount of butyryl 10 are given below, a duplicate having also been run.

	1	2
M =	32.33 c. c.	37.20 c. c.
M ₁ =	23.78 c. c.	27.27 c. c.
M ₂ =	14.53 c. c.	16.62 c. c.
K ₁ = $\frac{100 M_1}{M}$	73.5	73.3
K ₂ = $\frac{100 M_2}{M}$	44.9	44.7

After substitution of K₁ and K₂ in the appropriate equations given, the molar percentages of the three acids in the distillate are found to be 25 as follows:

	1	2
	Percent	Percent
A =	73.2	72.6
P =	23.4	23.8
B =	3.4	3.6

The apparent acetyl value (all the acyl calculated in terms of acetyl) is 42.2%. Thus the percentage of each of the three acyl groups in the ester will be found to be:

	1	2
Acetyl	30.9	30.5
Propionyl	13.1	13.3
Butyryl	2.2	2.5

As was pointed out above the present invention also includes the analysis of a mixture of two or all of the fatty acids of 2-4 carbon atoms, and is accurate even when butyric acid is present in only small amounts. The following data illustrate the accuracy of this analysis with various mixtures of the three acids in varying proportions:

	Acetic	Propionic	Butyric
	Percent	Percent	Percent
Mixture #1	Found.....	51.1	24.6
	Taken.....	50.7	24.3
Mixture #2	Found.....	25.5	69.8
	Taken.....	25.8	69.2
Mixture #3	Found.....	21.0	68.5
	Taken.....	20.6	69.3
Mixture #4	Found.....	9.4	23.9
	Taken.....	10.2	24.6
			65.2

As pointed out above other liquid fatty acid esters of the lower monohydroxy alcohols which are substantially insoluble in water such as n-butyl acetate, ethyl n-butyrate, ethyl propionate, isobutyl acetate, n-propyl butyrate and the like are suitable for use as extractants in the analysis of cellulose esters in accordance with the present invention. As n-butyl acetate has a comparatively wide range from the value of K₁ for acetic acid to the value of K₂ for butyric acid it is particularly desirable for use in accordance with the present invention.

We claim as our invention:

1. A method of analysis of a mixture of fatty acids of 2-4 carbon atoms which comprises titrating a given quantity of the mixture with standard alkali, extracting a measured amount of the mixture in aqueous condition with a predetermined amount of an extractant comprising a liquid fatty acid ester of a lower aliphatic monohydroxy alcohol which is substantially insoluble in water, removing the aqueous layer therefrom, titrating an amount of that aqueous layer, corresponding to the amount of mixture which is titrated, with standard alkali, extracting another like amount of the mixture in aqueous condition with an excess of the same type of extractant, removing the aqueous layer and titrating an amount, corresponding to that titrated above, with standard alkali, determining the percentage partition coefficient designated as K₁ and K₂ in accordance with the formulas:

$$K_1 = \frac{100 M_1}{M}$$

$$K_2 = \frac{100 M_2}{M}$$

where M represents the amount of alkali used in the titration of the mixture before extraction, M₁ represents the amount of alkali used in the titration of the aqueous layer when a small amount of extractant was used and M₂ represents the amount of alkali used in titration of the aqueous layer when a large amount of extractant was used, and then mathematically determining the contents of the various acids in the mixture from these percentage partition coefficients and the percentage partition coefficients of the individual acids in the two amounts of extractant employed.

2. A method of analysis of a cellulose ester containing a plurality of fatty acid groups of 2-4 carbon atoms which comprises completely hydrolyzing the ester with aqueous alkali, treating with a high boiling mineral acid in an amount chemically equivalent to the alkali metal content, distilling the resulting mass to obtain all of the lower fatty acid in the form of a distillate, titrating a given amount of the distillate with standard alkali, extracting a measured amount of the distillate with a predetermined amount of an extractant comprising a liquid fatty acid ester of a lower aliphatic monohydroxy alcohol which is substantially insoluble in water, removing the aqueous layer therefrom and titrating an amount, corresponding with the amount of distillate previously titrated, with standard alkali, extracting another like amount of distillate with an excess of a like extractant, removing the aqueous layer and titrating with standard alkali as before, determining the percentage partition coefficients which may be designated K₁ and K₂ in accordance with the formulas:

$$K_1 = \frac{100 M_1}{M}$$

$$K_2 = \frac{100 M_2}{M}$$

where M represents the amount of alkali used in the titration of the distillate before extraction, M₁ represents the amount of alkali used in the titration of a given amount of aqueous layer when a small amount of extractant was used and M₂ represents the amount of alkali used in the titration of the same amount of the aqueous layer when a large amount of extractant was used and then mathematically determining the contents of

the various acyls from these percentage partition coefficients and the percentage partition coefficients of the individual acids of the two amounts of extractant employed.

- 5 3. A method of analysis of a mixture of acetic acid with only one fatty acid of 3-4 carbon atoms which comprises titrating a given amount of the mixture with standard alkali, extracting a measured amount of the mixture with a liquid fatty acid ester of a lower aliphatic monohydroxy alcohol which is substantially insoluble in water, removing the aqueous layer and titrating an amount of that layer, corresponding to the amount of mixture previously titrated, with standard alkali, determining the percentage partition coefficient which may be designated K_1 in accordance with the following formula:

$$K_1 = \frac{100M_1}{M}$$

20 where M represents the amount of alkali used in the titration of the distillate before extraction, and M_1 represents the amount of alkali used in the titration of the aqueous layer formed when the extractant was employed on the mixture, then determining the propionyl or butyryl in accordance with the following formula:

$$P \text{ or } B = \frac{100k_1 - K_1}{k_1 - a}$$

30 where k_1 is the percentage partition coefficient of acetic acid with the amount of extractant employed in the extraction and a is the percentage partition coefficient of the fatty acid of 3-4 carbon atoms with the amount of extractant employed in the extraction.

4. A method of analysis of a cellulose ester containing only acetyl groups and groups of one fatty acid of 3-4 carbon atoms which comprises 40 completely hydrolyzing the ester with aqueous alkali, treating with a high boiling mineral acid in an amount chemically equivalent to the alkali metal content, then distilling to obtain all the lower fatty acids in the distillate, titrating a given amount of the distillate with a liquid fatty acid ester of a lower aliphatic monohydroxy alcohol which is substantially insoluble in water, removing the aqueous layer therefrom and titrating an amount of this aqueous layer, corresponding to that of the distillate titrated, with standard alkali, determining the percentage partition coefficient which may be designated K_1 in accordance with the formula:

$$K_1 = \frac{100M_1}{M}$$

55 where M represents the amount of alkali used in the titration of the distillate before extraction and M_1 represents the amount of alkali used in the titration of the aqueous layer when a small amount of extractant is used, then determining the propionyl or butyryl in accordance with the following formula:

$$P \text{ or } B = \frac{100k_1 - K_1}{k_1 - a}$$

65 where k_1 is the percentage partition coefficient of acetic acid with the amount of extractant employed in the extraction and a is the percentage partition coefficient of the fatty acid of 3-4 carbon atoms with the amount of extractant employed in the extraction.

- 70 5. In the method of determining the percentage partition coefficient of a mixture of fatty acids of 2-4 carbon atoms to be used in the de-

termination of the acyl content of that mixture the steps which comprise extracting the mixture in aqueous condition in a predetermined amount of an extractant comprising a liquid fatty acid ester of a lower aliphatic monohydroxy alcohol which is substantially insoluble in water and then titrating a given amount of the aqueous layer formed by that extraction with standard alkali.

- 5 6. In a method of determining a percentage partition coefficient of a mixture of fatty acids of 2-4 carbon atoms for use in determining the relative acyl contents of that mixture, the steps which comprise extracting a given amount of the mixture with the mixture in aqueous condition 15 with a predetermined amount of normal propyl acetate, removing the aqueous layer therefrom and titrating a given amount of the aqueous layer with standard alkali.

7. In a method of determining a percentage partition coefficient of a mixture of fatty acids of 2-4 carbon atoms for use in determining the relative acyl contents of that mixture, the steps which comprise extracting a given amount of the mixture with the mixture in aqueous condition 25 with a predetermined amount of normal butyl acetate, removing the aqueous layer therefrom and titrating a given amount of the aqueous layer with standard alkali.

8. A method of analysis of a cellulose ester 30 containing a plurality of fatty acid groups of 2-4 carbon atoms which comprises completely hydrolyzing the ester with aqueous alkali, adding thereto a high boiling acid in an amount chemically equivalent to the alkali metal content, distilling the mass to obtain all the lower fatty acid therefrom as a distillate, titrating a given amount of that distillate, extracting a measured amount of the distillate with normal propyl acetate, removing the aqueous layer and titrating, 40 an amount of that layer, corresponding to the amount of distillate titrated, with standard alkali, extracting another like measured amount of distillate with an excess of normal propyl acetate, removing the aqueous layer and titrating an 45 amount of that layer, corresponding to the amount of the distillate titrated, with standard alkali, determining the percentage partition coefficients which may be designated K_1 and K_2 in accordance with the formulas:

$$K_1 = \frac{100M_1}{M}$$

$$K_2 = \frac{100M_2}{M}$$

55 where M represents the amount of alkali used in the titration of distillate before extraction, M_1 represents the amount of alkali used in the titration of the aqueous layer when a small amount of extractant was used and M_2 represents the amount of alkali used in the titration of the aqueous layer when a large amount of extractant was used and then calculating the propionyl content P in accordance with the following formula:

$$P = \frac{\frac{K_1 - 100k_1}{k_2 - k_1} - K_2}{\frac{k_2 - k_1}{k_2 - k_4} - \frac{k_3 - k_4}{k_3 k_4}} = \frac{100k_4}{k_2 - k_1 - \frac{k_3 - k_4}{k_3 k_4}}$$

70 in which k_1 equals the percentage partition coefficient of an amount of .1 N acetic acid corresponding to the amount of aqueous layer extracted with the smaller amount of propyl acetate employed in the extraction, k_2 is the percent-

age partition coefficient under like circumstances of propionic acid, k_3 is the percentage partition coefficient under like conditions of butyric acid, k_4 is the percentage partition coefficient of the designated amount of the 0.1 N acetic acid with the excess quantity of propyl acetate used in extraction, k_5 and k_6 are the percentage partition

coefficients under like conditions of propionic and butyric acid respectively, or the butyryl content B in accordance with an equivalent formula.
